(57) **CLAIM**

The ornamental design for a turbo fan, as shown and described.

DESCRIPTION

FIG. 1 is a front perspective view of a turbo fan showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of FIG. 2;

FIG. 10 is a partial enlarged view of FIG. 2; and,

FIG. 11 is a perspective view of the turbo fan in a state of use.

The broken lines in the drawings illustrate the portions of the turbo fan, which form no part of the claimed design. The dot-dash broken lines in FIG. 2, FIG. 9, and FIG. 10 represent the boundary of the enlarged portion and forms no part of the claimed design.

1 Claim, 11 Drawing Sheets
